UNITED STATES PATENT OFFICE

LEMUEL R. MEARS, OF BROOKLYN, NEW YORK.

IMPROVEMENT IN BOOT AND SHOE NAILING MACHINES.

Specification forming part of Letters Patent No. **152,146**, dated June 16, 1874; application filed May 16, 1874.

To all whom it may concern:

Be it known that I, LEMUEL R. MEARS, of Brooklyn, in the county of Kings and State of New York, have invented a new and Improved Machine for Nailing Boots and Shoes, of which the following is a specification:

The object of the invention is to provide a power-machine for nailing on the soles of boots and shoes, and at the same time automatically feeding the shoe or boot, and supplying the nails. For the nails I propose to use the kind made in the form of a long comb, and now used with hand nailing-machines, the nails being connected together by the heads, so as to feed into the machine like a bar, and be detached, one by one, as they are driven. The invention consists of a nail-driver and a bender, arranged together in a stock, and geared by rock-levers with cams for operating them; also, automatic feed mechanism, for feeding the nails to the driver; and, also, automatic feed mechanism, for feeding the boot or shoe, all so combined and arranged that the nail-bar and the boot or shoe feed along simultaneously; and immediately after each feed-movement the bender moves down a little in advance of the driver to adjust the nail to the driving-channel, and then the driver moves down and drives the nail into the shoe.

Figure 1 is a front elevation of my improved machine. Fig. 2 is a sectional elevation taken on the line *x x*, Fig. 1. Fig. 3 is a sectional elevation taken on the line *y y*, Fig. 2. Fig. 4 is a horizontal section taken on the line *z z*, Fig. 3. Fig. 5 is a vertical section on the line *w w* of Fig. 4, and Fig. 6 is an end elevation of the feed-channel for the nails. Fig. 7 is a detail of the nail-driver and rod.

Similar letters of reference indicate corresponding parts.

A represents the nailing-stock, containing the nail-driver *B*, the bender *C*, and the cutter *D*, for cutting the nails *a* off from the comb-bar *F*, and driving them down through the channel *G* into the sole of the boot or shoe, which is to be fed along under the nozzle-shaped termination *H* of the lower end of the stock *A*. The nail-driver *B* is connected to a rod, *I*, fitted in the stock *A*, to work up and down, and connected to the rock-lever *J*, which

is connected with the cam-disk *K*, so that the cam *L* forces the driver down, and the rim or flange raises and holds it up. The bender *C* is connected to rod *N*, which works in a longitudinal groove, *O*, in the rod *I*, and is connected to the rock-lever *P*, which is also connected with the cam-disk *K*, so that the cam *Q* forces the bender down and holds it while the driver cuts off and drives the nail, and the rim or flange *R* raises and holds the bender up. Springs may be used instead of flanges for raising the driver and the bender. The bender is to turn the nail down into the line of the driving-channel *G* after it has passed beyond the cutter into said channel, the way on which the nail-bar is fed into the stock being a little inclined, and the end of the cutter being also inclined, so that when the nail arrives under the driver it points obliquely to one side of the channel, which is necessary for the nail-bar to run properly on the ways. The bender-rod *N* has a wide rib, *P'*, which works in a vertical slot, *Q'*, in the upper part of the stock *A*, which, together with the rod *N* working in the slot *O* of the driver-stock, keeps the stock from turning out of its true position. *R'* is the channeled way in which the nail-bar is placed to be fed into the nailing-stock, said way being arranged horizontally behind the stock *A*, and entering it at the side, as seen in Figs. 3, 4, and 5. The channel is made in two parts, *a* and *b*, at right angles to each other, *a* being for the shanks of the nails, and *b* for the flange of the nail-bar, forming the heads of the nails when the nails are cut off. The channel is a little inclined from the vertical plane, as shown in Figs. 3 and 6, in order that the nail-bars will lie in it alike, although they may vary somewhat in size.

The nails are fed along, one at a time, into the stock *A* by the pawl *S*, which I propose to mount on a slide, *T*, in ways *U*, on the side of the feedway *R*, near the nailing-stock *A*; and I connect the slide to a rock-lever, *V*, by a rod, *W*, having an adjusting-joint, *X*, and the rock-lever is connected with the cam-disk *K*, so that the cam *Q* throws the pawl forward to feed the nails. The spring *Y* pulls the pawl back against an adjusting-screw, *Z*, by which the movement of the pawl is regu-

lated to correspond with the distance from nail to nail, while the adjusting-joint X regulates the position of the pawl with reference to the nail-driving channel. The spring *m* prevents the nails from moving back with the feed-pawl.

The boot or shoe is fed by the pawl *d*, which is worked by the cam *e*, rock-lever *f*, and connecting-rod *g*. *h* is a holding pawl or presser. The boot or shoe, with the last in it, will be presented under the nozzle *H* of the stock on any suitable holder, and guided by the operator, so that the pawl *d* will work in the channel formed in the sole for the nails.

The mechanism here represented for feeding the boot or shoe is the same as is used in a machine for sewing shoes, and I do not claim it, especially; and the way for feeding the nail-bar is also similar to that used in hand nailing-machines.

The nail-driver *B* is subjected to considerable wear, and requires to be ground off square on the end, from time to time, so that it shortens gradually, and it is subject to too much strain to be held by a set-screw acting against its side. Therefore, I have arranged an eccentric cam, *i*, in a socket in the rod, for sustaining the force of the shocks on the driver, and for adjusting to follow the driver, as it has to be let down from time to time.

Having thus described my invention, I

claim as new and desire to secure by Letters Patent—

1. The combination, in a boot and shoe nailning machine, of the nail-bender and nail-driver, having rock-levers *J* and *P* and cams *L* and *Q*, arranged to operate them independently of, but relatively to, each other, in the order described.

2. The combination, with the slotted feed-channel, of the nail-feeding pawl attached to a horizontally-reciprocating slide, rod *W*, lever *V*, cam *Q*, and spring *Y*, substantially as shown and described, said pawl being thus arranged for operating independently of the nail-driver, as set forth.

3. The combination, with the stock or head *A*, bender, and driver, of automatic feed mechanism, for feeding the boot or shoe, substantially as specified.

4. The combination of the adjustable eccentric with the nail-driver *B* and rod *I*, substantially as specified.

5. The combination of the bender-rod *N*, having rib *P'*, with the driver-rod *I* and stock *A*, provided, respectively, with grooves *O* and *Q'*, substantially as and for the purpose specified.

LEMUEL R. MEARS.
